UNITED STATES PATENT OFFICE.

HYACINTH ALPHONSE POVEL, OF BUSSUM, NETHERLANDS.

HOLDER FOR SHAVING SOAP.

Application filed May 11, 1920. Serial No. 380,591.

To all whom it may concern:

Be it known that I, HYACINTH ALPHONSE POVEL, a subject of the Queen of the Netherlands, residing at Bussum, Province of North Holland, Kingdom of the Netherlands, have invented certain new and useful Improvements Relating to Holders for Shaving Soap, of which the following is a specification.

10 The invention relates to holders for shaving soap. The holder according to the invention consists of a case of, preferably, cylindrical form closed at its lower end by a removable cover and containing discs of soap 15 adhering together by their adjacent plane surfaces.

The arrangement has the advantage that no soap is wasted, since the whole of the discs can be used. Also, it is not necessary 20 to hold the soap itself in the hand as is usually the case in known shaving soap sticks.

There is also the advantage that a softer soap can be employed than is possible with the soap sticks now in use. In these latter, 25 soap of harder consistency must be used than would be desired for this purpose, since the soap sticks would otherwise soon loose their shape.

The holder according to the invention is 30 filled with discs of shaving soap, so that the contents project only slightly from the case. After a disc has been used up, the holder is filled up again by inserting from the bottom a fresh disc, which by the cohesion of its 35 upper surface forms one mass with the other discs present in the holder.

The bottom cover of the case may be provided with a central projection which is either connected with the cover itself or is 40 simply resting loosely on the flat bottom of same. This projection is pressed against the under side of the discs when the cover is adjusted longitudinally relative to the case.

Also, according to the invention the case 45 may be divided transversely and may consist, for example, of two parts screwed together. The soap may then be used until the top of the upper disc is level with the top of the upper part of the case. This upper part is then unscrewed and the holder 50 can be used without inserting a new disc.

Also, a sheet of flexible material, such as cork, corrugated paper, or the like can be inserted between the adhering soap discs and the wall of the case. The inner wall of the holder can then adapt itself to any change of form of the discs. Also, each disc for a small portion of its end surfaces may be of a softer consistency than the rest of the disc in order to improve the cohesion between the adjacent discs.

Examples of constructions according to the invention are shown in the accompanying drawings. Fig. 1 is a longitudinal section; Fig. 2 is a front view of the holder; Fig. 3 is a longitudinal section through a modified construction; Fig. 4 is a longitudinal section of the lower cover of the construction shown in Fig. 3; Fig. 5 shows a cross section through a soap disc enclosed by a flexible material; Figs. 6 and 7 show under different conditions longitudinal sections through a modified form; Figs. 8 and 9 are longitudinal sections through a still further modification.

The same references are used for similar parts in all the figures.

Referring more particularly to Figs. 1 and 2 the holder consists of a cylindrical case 2 the lower part of which has a screw 30 thread 3 engaging with a thread 7 on the lower cover. The cover may also be fastened on by a bayonet joint or by clamping. The top of the case 2 is closed by a cover 5 which rests on a pressed out embossment of 35 the periphery 4 of the case.

The cover 5 can be screw threaded to the case or fastened by a bayonet joint. The soap discs 1 are inserted into the case 2 from the under side after removal of the cover 6. 40 The thickness of the disc is such that only a small part of the upper disc is enclosed by the case 2, so that before it has been reduced by use the greater portion projects from the case. Between the cover 6 and the lowest 45 of the discs 1 there is, preferably, a plate 9 of glass, celluloid or other suitable material, so that the inside of the cover is always clean, or a disc of paper or cartridge may be inserted to prevent adhesion between the 50 plate 6 and the soap.

Preferably, between the outer surfaces of

the soap discs and the inner walls of the case 2 a sheet 8 of cork, felt, or other flexible material is inserted, so that the wall of the case can adapt itself to the alterations of shape which the relatively soft mass of soap may undergo in use. When the top soap disc has been consumed so that its upper surface is level with the upper edge of the case, the cover 6 is unscrewed, another disc of soap 16 is inserted in contact with the lowest disc remaining in the case and the whole contents are pressed in so as to allow the plate 6 to be again put on. The top disc when the bottom cover has been screwed up, projects from the holder and is held in position by its adhesion to the rest of the contents. The amount which the soap stick projects from the case can be regulated as required by screwing the cover 6. The whole contents of the case can be removed by the finger by pressure applied from below and when a new disc has been placed in the case on the plate 9 the remainder, in the form of an adherent mass, can be inserted from 25 above on the new disc.

The bottom of the case 2 can be flanged inwards to form an annular support for the discs, inserted from above.

In the construction shown in Figs. 3 and 30 4 the upper edge is somewhat constricted at 10 in order to clamp the top disc and prevent the entrance of foreign matter. Rings 13 of corrugated paper or corrugated cartridge at this part provide a certain amount 35 of elasticity.

The cover 6 is provided with an upwardly projecting part 11, the top 12 of which can be screwed against the contents of the case so as to raise them as required.

40 Fig. 5 is a cross section through the soap disc with a ring of corrugated paper or other suitable material 13 covered with tin-foil 14.

45 On inserting a fresh disc of soap, the ring enclosing the disc is inserted with it, the top ring in the case being forced out. Since the flexible rings are only used for a short time, they do not lose their elasticity by the entrance of water which is also prevented as far as possible by the covering of tin-foil.

50 In the construction shown in Figs. 6 and 7 the top of the case 2 is bent over at 15 and within the case at this end there is a ring 55 16 of rubber, cork, or other elastic material, which is inserted from below and is pressed against the bent over edge of the case. The inner diameter of this ring corresponds to that of the bent over edge of the case. Below the ring 16 there is a ring 17 of hard 60 material, wood, metal or the like, which surrounds the soap discs with a little clearance. The combined height of the ring 16 and of the ring 17 is rather more than that of the 65 case 2. On screwing up the holder the cover 6

is pressed against the ring 17 and indirectly against the ring 16. By the pressure exerted the inner diameter of the ring is reduced as shown in Fig. 7 and the soap at this place is closely held.

70 In the construction shown in Figs. 8 and 9, the holder consists of ebonite, celluloid or other such suitable material. Within the case 2 there is a tube 18 on the outside of which is a circular projection 19. The tube 75 is cut at 20 and can, therefore, be compressed to a smaller diameter. On the inner wall of the case 2 there is an annular recess 21 in which the projection 19 of the ring 18 fits, so that the ring 18 when the cover 6 is unscrewed, by its elasticity causes the projection 19 to lie in the recess 21. When the cover 6 is screwed on, the bottom of the cover presses against the lower surface of the ring 18 and displaces it upwards. 80 The projection 19 is forced out of the recess 21 and compresses the ring 18 which clamps the content of the case.

85 The upper edge of the ring 18 may be rounded off to correspond with the upper 90 surface of the case 2.

Between the cover 6 and the lowest of the soap discs there may be a plate 9 of glass, celluloid or other material. In order to be able to facilitate the removal of the ring 18 95 from the case 2 after the contents have been taken out, a projecting edge 22 can be provided.

98 What I claim is:

1. In combination, a tubular open-ended 100 holder having a length substantially equal to its diameter and also having a restricted upper end, plastic soap disks arranged in superposed relation in the holder and each having a diameter greater than the diameter of the opening at the restricted upper end of said holder, and a removable cover adjustably connected to the base of said holder and bearing against the lowermost disk and exerting pressure on the disks to cause the disks to adhere to each other at their contacting surfaces and to form a substantially integral stick into which the restricted upper end indents itself, the extent of adjustment of said cover being approximately 105 equal only to the thickness of a soap disk.

2. A combination of the kind defined by claim 1 in which the adjustable cover is provided with an upwardly projecting portion adapted to engage the lowermost one of 110 said disks.

115 3. A combination of the kind defined by claim 1 in which an elastic ring is arranged between the inner surface of the holder and the soap disks, and in which the adjustable cover is engageable with said ring to cause the same to be compressed by the holder for clamping the upper one of said disks in the holder.

120 4. A holder for shaving soap including a 125

tubular casing having an annular groove on its inner circumference, a split clamping ring mounted in the casing and having a substantially annular shoulder engaging said annular groove, a series of superposed soap disks mounted in the ring and holder, and a cover adjustably connected to the casing and engageable with said ring for moving the same axially in the casing to cause the shoulder to move out of the 10 groove and compress said ring. In testimony whereof I have hereunto set my hand this sixth day of April, 1920.

HYACINTH ALPHONSE POVEL.
